TOY FIGURE

William J. Maloney II, East Aurora, N.Y., assignor to
The Quaker Oats Company, Chicago, Ill.

Filed July 9, 1973, Ser. No. 377,521

Term of patent 14 years

Int. Cl. D21—01

U.S. Cl. D34—4 R

FIG. 1

FIG. 2

FIG. 3

FIG. 1 is a front prospective view of a toy figure showing my new design, with the lower portions folded forwardly;

FIG. 2 is a front elevational view of the toy figure with the lower portions lying substantially coplanar with the remaining portions of the toy;

FIG. 3 is a rear elevational view of the toy figure as shown in FIG. 2; and

FIG. 4 is a top plan view of the toy figure as shown in FIGS. 2 and 3.

I claim:

The ornamental design for a toy figure, substantially as shown.
